Letters Patent No. 3356. Dated July 17, 1866.

Design for Paper Cuffs.

The schedule referred to in the Letter Patent, and making part of the same.

To all whom it may concern.

Be it known that I, B. G. Briggs of Providence in the County of Providence and State of Rhode Island have invented a Design for Paper Cuffs; and I do hereby declare that the following is a full, clear, and exact description thereof which will enable any one skilled in the art to make and use the same, reference being had to the accompanying drawing forming part of this specification.

The drawing represents a side elevation of this invention.

This invention relates to a paper cuff which is ornamented by a series of stripes of gradually increasing width and placed at gradually increasing distances apart in such a manner that a cuff is produced which presents an ornate and elegant appearance.

A, represents a cuff which is ornamented by a series of stripes a. — These stripes are of gradually increasing width, the narrowest being nearest to the edge, and they are placed at gradually increased distances apart as shown in
